WATER DEMINERALIZER UNIT

Leo Kolodny, Washington, D. C.

Application April 10, 1953, Serial No. 24,453

Term of patent 14 years

(Cl. D91—1)

To all whom it may concern:

Be it known that I, Leo Kolodny, a citizen of the United States, residing at Washington, in the District of Columbia, have invented a new, original, and ornamental Design for a Water Demineralizer Unit, of which the following is a specification, reference being had to the accompanying drawing, forming a part hereof.

Figure 1 is a side elevational view of a water demineralizer unit showing my new design; Figure 2 is a front elevational view thereof; Figure 3 is a section taken on line 3—3 of Figure 2 looking in the direction of the arrows.

The top surfaces not shown are substantially plain.

I claim:

The ornamental design for a water demineralizer unit, as shown and described.
